COMBINED COUNTING AND PRINTING
MACHINE

William O'Neil, New York, N. Y., assignor to Pitney-Bowes, Inc., Stamford, Conn., a corporation of Delaware

Application March 16, 1950, Serial No. 8,574

Term of patent 14 years

(Cl. D64—11)

To all whom it may concern:

Be it known that I, William O'Neil, a citizen of the United States, residing at New York, in the county of New York and State of New York, have invented a new, original, and ornamental Design for a Combined Counting and Printing Machine, of which the following is a specification, reference being had to the accompanying drawing, forming part thereof; wherein:

Fig. 1 is a perspective view of a combined counting and printing machine taken in the direction of the top, rear and one end thereof showing my new design; and

Fig. 2 is a perspective view similar to Fig. 1, taken in the direction of the top, front and opposite end of the machine.

I claim:

The ornamental design for a combined counting and printing machine, as shown and described.

WILLIAM O'NEIL.
